(57) **CLAIM**

The ornamental design for a helical strain relief device, as shown and described.

DESCRIPTION

FIG. 1 is a top left perspective view of a helical strain relief device.

FIG. 2 is a front elevation view of the helical strain relief device.

FIG. 3 is a back elevation view of the helical strain relief device.

FIG. 4 is a right elevation view of the helical strain relief device.

FIG. 5 is a left elevation view of the helical strain relief device.

FIG. 6 is a top plan view of the helical strain relief device; and,

FIG. 7 is a bottom plan view of the helical strain relief device.

The broken lines shown represent the portions of the helical strain relief device that form no part of the claimed design.

1 Claim, 4 Drawing Sheets
